ABSTRACT OF THE DISCLOSURE

A faller bar for textile machinery comprises a molded body of synthetic resin having the butt ends of a series of pins imbedded therein, and there being a longitudinal resilient metal reinforcing element permanently imbedded within the body to extend between the end mounting sections of the bar adjacent the pin butt ends.

A faller bar for a textile combing machine, for example a gill box, comprises a metal bar having its end portions adapted for engagement with traversing mechanism, the intermediate portion of the metal faller bar having a series of pins projecting, in comb-like fashion, from one edge of the bar, for operating on fibres to be combed. The conventional method of securing the pins to a faller bar comprises forming a series of holes in one edge of the metal faller bar and securing a pin in each hole. It has also been proposed to provide a pin strip unit comprising a strip of synthetic resin in which the butt ends of a series of pins are embedded, the pin strip unit being adapted to be secured in a longitudinally disposed groove in the faller bar.

According to the present invention, a faller bar or other comb-like member is formed by molding the faller bar or the like around the butt ends of a series of pins. The pins will therefore be permanently secured to the faller bar or the like so that when the pins become worn or broken, the entire faller bar will be discarded and then be replaced by a fresh faller bar, instead of extracting and replacing individual pins or pin strip units as would be done with conventional or previously proposed metal faller bars. By molding the faller bar from synthetic resinous material, a replacement faller bar may cost no more than the cost of removing worn pins or pin strip units and replacing them by new pins or pin strip units, and could possibly involve even less expense than such renewal of pins or pin strip units. The pins may be held in a jig whilst the faller bar is being moulded around the butt ends of the pins.

The faller bar may be formed in a mold of any convenient construction, the internal cavity of the mold being formed according to the shape and size of the particular faller bar being produced. The mold may have an opening along the side or edge where the pins are to project from the faller bar, and a jig carrying the series of pins held therein in parallel closely spaced disposition with the butt ends of the pins only projecting from the jig, may be disposed over the said opening in the mold with the butt ends of the pins projecting into the cavity of the mold. The jig therefore serves to close the mold, and the butt ends of the pins will be embedded in the material of the faller bar when the molding material is injected or otherwise inserted into the mold.

The butt ends of the pins may be formed so as to "key" into the material molded around them, for example they may have heads, or be flattened or they may be bent or otherwise formed to resist withdrawal of the pins after the material of the faller bar has set.

2

The faller bar may have a metal insert or reinforcement, and such metal insert or reinforcement may extend throughout most of the length of the faller bar. Preferably the metal insert will be of resilient material, for example spring steel, so that if the faller bar should be bent or flexed due to stresses during use, it will return to its original form when such stresses are released. In the production of a faller bar with metal inserts or reinforcement, the metal insert may be placed in the mold so that the faller bar will be molded around the metal insert as well as around the butt ends of the pins.

A faller bar constructed according to the invention together with modifications and a method of making the faller bar will now be described, by way of example only, with reference to the accompanying drawings, in which:

FIGURE 1 is a side elevation of the faller bar,

FIGURE 2 is an end elevation of the faller bar of FIGURE 1,

FIGURE 3 is a side elevation, partly in section, of one end portion of the faller bar of FIGURE 1, drawn to a larger scale,

FIGURE 4 is a view similar to FIGURE 3, but showing a modification,

FIGURE 5 is a cross-section on the line V—V of FIGURE 4,

FIGURE 6 is a plan view, partly in section, of the end portion of the faller bar shown in FIGURE 5,

FIGURE 7 is a cross-section through a faller bar showing a modification,

FIGURE 8 is a detail sectional view of part of a faller bar showing a further modification, and

FIGURE 9 is a diagrammatic exploded perspective view of part of a mold, and a jig carrying metal pins and also a metal insert, for use in the manufacture of the faller bar.

Referring to the drawings, the simplest form of faller bar according to the invention is illustrated in FIGURES 1, 2 and 3. In these figures the faller bar body 10, which is of conventional size and shape, is molded around the butt ends of the pins 11 the main portions of which project from the upper surface of the body 10 as in a conventional faller bar. The body 10 is molded from a synthetic resinous material, a preferred material being glass filled nylon with which graphite is mixed. The glass filled nylon, comprising nylon reinforced with glass fibre, is tough and hard wearing, and the graphite provides a degree of self-lubrication for the faller bar.

In the modification shown in FIGURES 4, 5 and 6, the faller bar body 12 and the pins 13 are similar to the body 10 and pins 11 of FIGURES 1, 2 and 3, but in FIGURES 4, 5 and 6, a metal insert or reinforcement 14 is embedded in the body 12. The metal insert 14 is substantially U-shaped in cross-section and it extends throughout most of the length of the body 12. The insert 14 is disposed with its open side uppermost and the butt ends of the pins 13 are disposed between the two side walls of the insert but are not directly connected or attached to the insert 14. The end portions 15 of the insert 14 are flattened as shown in FIGURE 6, beyond the row of pins 13 so that these end portions 15 can extend into the narrower end portions of the body 12.

The modification shown in FIGURE 7 is similar to the arrangement of FIGURES 4, 5 and 6, in that a U-section insert 14 is embedded in the body 12 together with the butt ends of the pins 13, but the butt ends of the pins 13 are trapped or flattened as indicated at 16 for keying into the material of the body 12 so as to be securely retained therein.

An alternative arrangement for the same purpose is shown in FIGURE 8, in which the pins 17 have heads 18

on their butt ends embedded in the material of the faller bar body 19.

The method of manufacture of a faller bar according to the invention is illustrated in FIGURE 9. A mold 20 has a cavity 21 formed according to the shape and size of the particular faller bar to be produced. The cavity 21 is open at 22' along one side where the pins are to project from the faller bar, and a jig 22 comprising a bar has a series of holes 23 to receive a corresponding series of pins 24 therein, in parallel closely spaced disposition, with the butt ends 25 of the pins projecting from the inner side of the jig 22. The jig is intended to be placed over the open side 22' of the mold with the butt ends 25 of the pins 24 projecting into the cavity 21. In this particular example, a U-section metal insert or reinforcing strip 26 is also disposed within the cavity with the butt ends 25 of the pins disposed between the side walls of the insert 26, but it will be understood that the insert 26 may be omitted, for example when producing a faller bar as in FIGURES 1, 2 and 3. The jig 22 serves to close the open slide 22' of the mold cavity 21, and when the molding material is introduced into the mold, the butt ends 25, and the insert 26 if present, will be embedded in the material of the faller bar when the molding material sets. The insert 26 can be supported in the cavity 21 in any convenient or conventional manner. For example, the mold 20 may be used inverted, as compared with FIGURE 9, and the insert 26 placed over the butt ends 25 which will be projecting upwardly from the jig 22 which would also be inverted. The insert 26 will then be supported within the cavity 21 by the butt ends of the pins when the jig is fitted over the open side of the mold.

Any convenient moldable synthetic resinous material may be used for the faller bars. One such material is nylon reinforced with glass fibre which material is known as glass filled nylon, and, if desired, graphite may be incorporated to provide self-lubrication. However other material such as hard grades of polythene may be used. Advantages arising from the use of such materials for faller bars are reduction in noise when operating in a combing or like machine, reduced wear on the screws and cams of the machine, particularly if the cooperating screws or other members of the machine are made of similar materials. The faller bars will also be much lighter in weight than conventional metal faller bars.

Whilst the invention is primarily designed for application to faller bars, as described above, it will be understood that it can equally well be applied to other comb-like members that are normally made of metal and have a series of pins projecting therefrom and secured either individually or as pin strip units. For example, the invention can be applied to hackles and gills, French top combs and segments.

Although the metal insert or reinforcement illustrated in FIGURES 4, 5, 6, 7 and 9, is substantially U-shaped in cross-section, it will be appreciated that it may be of any other convenient cross-sectional shape, for example, it may comprise a plain metal strip and the end portions of the strip may be offset relatively to the main portion, and may be shaped according to the shape of the faller bar end portions so as to provide reinforcement as required for the faller bar end portions. In any event, the metal insert may have ribs or corrugations, for example longitudinally disposed ribs or corrugations, to increase the rigidity and resistance to flexing of the faller bar or the like.

Whilst it is preferred that a single metal insert should be embedded in the material of the faller bar, whether it is a plain strip or a corrugated or ribbed strip, there may be two such metal strips each disposed along one side of the butt ends of the pins. In any case whether there is one or two strips, or a U-section strip, it is preferred that the synthetic resinous material should be caused to fill all the spaces between the butt ends of the pins and be-

tween the metal insert or inserts and the butt ends of the pins.

We claim:

1. A lightweight comb-like member for a textile combing machine comprising a body molded of synthetic resin material and having integral end sections shaped for mounting the member in said machine, a series of pins arranged in a row along an intermediate section of said body disposed between said end sections with their butt ends permanently imbedded within said material and having pointed ends projecting from said body, and a longitudinally extending resilient spring metal reinforcing element permanently imbedded within said body to extend adjacent said butt ends of the pins and having its ends disposed and anchored within said body end sections, said element being shaped as a channel with the butt ends of the pins projecting through the open side thereof into the material filling said channel, and said element and said pins being independently incorporated within said body.
2. A lightweight comb-like member for a textile combing machine comprising a body molded of synthetic resin material and having integral end sections shaped for mounting the member in said machine, a series of pins arranged in a row along an intermediate section of said body disposed between said end sections with their butt ends permanently imbedded in said material and having pointed ends projecting out of said body, and a longitudinally extending resilient spring metal reinforcing element permanently imbedded within said body to extend adjacent the butt ends of said pins, said element being shaped as a channel with the butt ends of the pins projecting through the open side thereof into the material filling the channel, and said element and said pins being independently incorporated within said body.
3. A lightweight comb-like member for a textile combing machine comprising a body molded of synthetic resin material and having integral end sections shaped for mounting the member in said machine, a series of pins arranged in a row along an intermediate section of said body disposed between said end sections with their butt ends permanently imbedded within said material and having pointed ends projecting from said body, and a longitudinally extending resilient spring metal reinforcing element permanently imbedded within said body to extend adjacent said butt ends of the pins and having its ends disposed and anchored within said body end sections, said element and said pins being independently incorporated within said body.
4. The member defined in claim 3, wherein said material is nylon reinforced by incorporated glass fibers.
5. The member defined in claim 3, wherein said material contains an incorporated lubricating compound.
6. A lightweight comb-like member for a textile combing machine comprising a body molded of synthetic resin material and having integral end sections shaped for mounting the member in said machine, a series of pins arranged in a row along an intermediate section of said body disposed between said end sections with their butt ends permanently imbedded in said material and having pointed ends projecting out of said body, and a longitudinally extending resilient spring metal reinforcing element permanently imbedded within said body to extend adjacent the butt ends of said pins, said element and said pins being independently incorporated within said body.
7. The member defined in claim 6, wherein said element is a spring steel strip.
8. The member defined in claim 6 wherein said element is a channel shaped strip with its open side receiving the butt ends of said pins, and said element having flattened ends projecting within said integral body end sections.
9. A lightweight comb-like faller bar for a textile combing machine comprising a body molded in one piece

of synthetic resin material and having end sections integral with said body and shaped for mounting in said machine, longitudinally extending resilient spring metal reinforcing strip means permanently imbedded in said body, and a series of pins disposed in a row along the 5 section of said body intermediate said end sections, each of said pins having a butt end permanently imbedded in said material and shaped to anchor therein and having pointed ends projecting out of said body, said element and said pins being independently incorporated within 10

said body and said pins being wholly supported by said body material.
